GOVERNOR FOR INTERNAL-COMBUSTION ENGINES

Marion Mallory, Detroit, Mich.

Application June 26, 1944, Serial No. 542,058

13 Claims. (Cl. 123—103)

This invention relates to a governor for an internal combustion engine.

It is the object of this invention to produce a governor which is controlled by pressure conditions obtaining in the intake passageway and which is simple in structure and efficient in operation so that the speed of the engine will be accurately controlled with no substantial "hunting" or "surging" of the engine speed as the engine responds to different load conditions.

Fig. 1 is an elevation partly in section showing my governor.

Fig. 2 is an elevation partly in section showing my governor installed on the engine side of a carburetor.

Fig. 3 is a detail view of a choke ring.

Fig. 4 shows a modification of the governor shown in Fig. 2.

The elements which comprise my governor are as follows: governor housing 1 having an inlet 2 and an outlet 3, unbalanced governor 4, valve shaft 5, arm 6 fixed on valve shaft 5, spring 7, cylinder 8, piston 9, connecting rod 10 between arm 6 and piston 9, orifice 11, orifice 12, conduit 13 connecting orifices 11 and 12, branch conduit 14 connecting conduit 13 with cylinder 8, venturi 15 in conduit 13 which communicates through orifice 16 with conduit 14.

It should be noted that orifice 11 is positioned on the atmosphere side of throttle valve 4 so that as valve 4 closes the portion of the valve above shaft 5 swings away from orifice 11. Orifice 12 is positioned on the engine side of throttle valve 4 and on the opposite side of the vertical plane of valve 4 when open so that as valve 4 closes the portion of the valve below shaft 5 swings away from orifice 12. The portion of valve 4, Fig. 1, above shaft 5 is larger in area than the portion of valve 4 below shaft 5 so that the unbalance of the valve is such that the manifold suction tends to close the valve. By arranging orifices 11 and 12 so that the valve swings away from these orifices as it closes, the Venturi effect created by the valve and the intake passageway as the valve closes does not affect either orifice 11 or 12.

The governor shown in Fig. 2 is the same as that above described except that a different type of suction device is used. Instead of the suction device comprising cylinder 8 and piston 9, the suction device in Fig. 2 comprises a flexible diaphragm 17 in housing 18 which communicates only with conduit 14. Conduit 13 is provided with a variable restriction in the form of needle valve 19. 20 is a bypass conduit about restrict-

tion 19 from conduit 13 to orifice 22. 21 is a check valve in conduit 20.

The carburetor comprises the following parts: housing 23, venturi 24, inlet 25, throttle valve 26, fuel nozzle 27, fuel bowl 28, inlet 29 through which fuel flows from bowl 28 through nozzle 27, power jet 30, valve 31 controlling power jet 30, spring 32 normally holding valve 31 open, piston 33 connected to the stem of valve 31, cylinder 34, 10 conduit 35 connecting cylinder 34 with conduit 13. The carburetor is secured to the inlet end of governor housing 1 by bolts 36. For governing the engine at low speeds, a wafer 37 having an opening 38 for restricting the intake passageway is positioned between the carburetor and governor housings.

Operation.—In Fig. 2, the governor is shown installed under a carburetor and the engine is idling. As the carburetor throttle is opened wide, 20 the air velocity by orifices 11 and 12 will create a suction in suction device 18, causing suction device to overcome spring 7 and pull governor valve 4 towards a closed position. Governor valve 4, of course, is an unbalanced valve that tends to close as the suction is increased between it and the engine. Naturally, the suction device 18 starts the valve towards a closed position and the vacuum power between the valve 4 and the engine further assists the suction device in closing governor valve. As governor valve 4 starts to close, part of the charge flows into orifice 11 and out of orifice 12 by way of conduit 13, as indicated by arrows. This charge flowing through the small venturi 15 increases the suction at orifice 16 on the suction device 18, which also increases the power of the suction device. The operation of the governor shown in Fig. 1 is the same as above described. In both forms of governors, Figs. 1 and 2, as the suction device pulls 40 governor valve 4 toward closed position the manifold suction or vacuum at orifice 12 will increase but this high vacuum is not impressed upon diaphragm 17 or piston 9 because this high vacuum is bled down through orifice 11 and conduit 13. 45 In other words, orifice 11 changes from a suction orifice to an air bleed orifice when valve 4 moves toward closed position. When governor valve 4 closes, the vacuum in the manifold on the engine side of the governor valve might rise as high as 50 twenty-five inches of mercury whereas the vacuum in the suction device, due to the bleeding action of orifices 11 and 12, will only reach from, say, about seven inches to ten inches of mercury. This inter-action of orifices 11 and 12 to blend 55 down the vacuum in the suction device is bene-

ficial because it assists the governor valve to operate more smoothly and prevents surging or "hunting" of the engine, that is, abrupt and substantial changes in the speed of the engine from the governed speed as the governor valve opens and closes in response to changes in load on the engine. Should the engine start to slow down slightly due to increased load, the lower vacuum at orifice 12 permits spring 7 to start valve 4 toward open position. As governor valve 4 moves toward open position, the vacuum drops rapidly at orifice 12, but orifice 11 now becomes a suction orifice due to the increased velocity through the intake passageway by orifice 11 and thereby prevents a sudden drop of suction in the suction device.

When valve 4 is closed or partly closed and the engine operating under high vacuum, the vacuum is high in conduit 35, which moves piston 33 and valve 31 upwardly, closing inlet 30, which leans out the mixture. When inlet 30 is closed, the gasoline flow is through inlet 29. As throttle valve 4 moves toward an open position and the vacuum drops in conduit 35, valve 31 will open, permitting a richer mixture. Fuel now flows through both inlets 29 and 30.

The check valve 21 opens and permits a higher vacuum in the suction device 18 if the vacuum becomes excessive between valve 4 and the engine due to the engine overspeeding. Opening of valve 21 puts more power on suction device 18 and pulls valve 4 further towards a closed position.

The wafer 37 shown in Fig. 3 is placed between the carburetor and the governor if it is desired to govern the engine at real low engine speeds. When the wafer is used, a higher vacuum is maintained around orifices 11 and 12 when the engine is running at low speeds. If the wafer were not used and it was attempted to govern the engine at real low speeds, the velocity past orifices 11 and 12 would be low due to the low engine speed and the suction would not be high enough to start valve 4 closing until the engine had reached a speed higher than the desired governed speed.

The modified form of governor shown in Fig. 4 is identical with that shown in Fig. 2 except that a check valve 40 backed up by a compression spring 41 has been mounted in conduit 13 between venturi 15 and orifice 11 and a by-pass conduit 42 provided about said check valve 40. By-pass conduit 42 has a smaller diameter than conduit 13. Thus, when valve 4 closes to subject orifice 12 to the manifold vacuum, orifice 11 acts as an air bleed to orifice 12 through conduit 13 and by-pass conduit 42. If the manifold vacuum gets exceedingly high at orifice 12, then check valve 40 opens to thereby increase the air bleeding effect of orifice 11 on orifice 12.

I claim:

1. A device for controlling the speed of an internal combustion engine having an intake passageway comprising a governor valve in said passageway, a suction responsive device connected to said governor valve for controlling the same, a conduit connecting the suction device with the intake passageway on the atmosphere side of said governor valve, a second conduit connecting the suction device with the intake passageway on the engine side of said governor valve, a restriction in said second conduit, a bypass conduit around said restriction, said bypass conduit connecting said second conduit with the intake passageway on the engine side of the governor

valve, a check valve controlling said bypass conduit, said check valve being responsive to the suction in the intake passageway to open as the suction is increased due to the closing of the governor valve whereby the closing of the governor valve is accelerated.

2. In an engine governor having an intake passageway, a governor valve in said passageway, said governor valve being unbalanced so that the velocity of the fluid flowing through the intake passageway and the intake passageway suction tend to close said valve, an orifice in said intake passageway between the governor valve and the engine, an orifice in said intake passageway between the governor valve and the atmosphere, a conduit connecting said orifices, a suction device for controlling said governor valve and connected into the said conduit, an operative connection between the suction device and the governor valve, whereby the orifice between the governor valve and atmosphere plays the role of an air bleed to the other orifice when the said governor valve moves toward closed position and said orifice between the governor valve and atmosphere ceases to be an air bleed and becomes a suction orifice when the governor valve moves toward open position.

3. In an engine governor having an intake passageway, a governor valve in said passageway, said governor valve being unbalanced whereby the suction in the intake passageway on the engine side of the valve tends to close said governor valve, resilient means tending to open said valve, an orifice in the intake passageway between the governor valve and the engine, an orifice in the intake passageway between the governor valve and the atmosphere, a conduit connecting said orifices, a suction device for controlling said governor valve and connected into the said conduit, a connection between the suction device and the governor valve, whereby the orifice between the governor valve and atmosphere plays the role of an air bleed to the other orifice when the said governor valve moves toward closed position and said orifice between the governor valve and atmosphere ceases to be an air bleed and becomes a suction orifice when the governor valve moves toward open position.

4. In an engine governor having an intake passageway, a governor valve in said intake passageway, an orifice in said passageway between the governor valve and the engine, an orifice in said passageway between the governor valve and atmosphere, a conduit connecting said orifices, a venturi in said conduit, a suction device for controlling said governor valve, a second conduit connecting said suction device with the venturi in said first-mentioned conduit, a connection between the suction device and the governor valve, whereby the orifice between the governor valve and atmosphere plays the role of an air bleed to the other orifice when the said governor valve moves toward closed position and said orifice between the governor valve and atmosphere ceases to be an air bleed and becomes a suction orifice when the governor valve moves toward open position.

5. In an engine governor having an intake passageway, a governor valve in said intake passageway, said governor valve being unbalanced whereby the suction in the intake passageway on the engine side of the valve tends to close said governor valve, an orifice in said passageway between the governor valve and the engine, an orifice in said passageway between the governor

valve and atmosphere, a conduit connecting said orifices, a venturi in said conduit, a suction device for controlling said governor valve, a second conduit connecting said suction device with the venturi in said first-mentioned conduit, a connection between the suction device and the governor valve, whereby the orifice between the governor valve and atmosphere plays the role of an air bleed to the other orifice when the said governor valve moves toward closed position and said orifice between the governor valve and atmosphere ceases to be an air bleed and becomes a suction orifice when the governor valve moves toward open position.

6. In combination a carburetor for an internal combustion engine, a governor including a housing having a passageway therethrough mounted between the carburetor and the engine, a member having an opening therethrough which serves as a restriction for the motive fluid flowing through the carburetor into the governor housing, said member being positioned between the governor housing and the carburetor, a governor valve mounted in the passageway in said housing, a suction device, a conduit connecting the suction device with the passageway in the governor housing on the engine side of the governor valve, a connection between the suction device and the governor valve whereby the suction device responds to a fall in the pressure in the intake passageway on the engine side of said governor valve and moves said governor valve toward closed position.

7. In combination a carburetor for an internal combustion engine, a governor including a housing having a passageway therethrough mounted between the carburetor and the engine, a member having an opening therethrough which serves as a restriction for the motive fluid flowing through the carburetor into the governor housing, said member being positioned between the governor housing and the carburetor, a governor valve mounted in the passageway in said housing, a suction device, a conduit connecting the suction device with the passageway in the governor housing on the engine side of the governor valve, a second conduit connecting the suction device with the passageway in the governor housing between the restricting member and the governor valve, a connection between the suction device and the governor valve whereby the suction device responds to a fall in the pressure in the intake passageway on the engine side of said governor valve and moves said governor valve toward closed position.

8. In combination a carburetor for an internal combustion engine, a governor including a housing having a passageway therethrough mounted between the carburetor and the engine, a metal wafer having an opening therethrough which serves as a restriction for the motive fluid flowing through the carburetor into the governor housing, said metal wafer being positioned between the governor housing and the carburetor, a governor valve mounted in the passageway in said housing, a suction device, a conduit connecting the suction device with the passageway in the governor housing on the engine side of the governor valve, a connection between the suction device and the governor valve whereby the suction device responds to a fall in the pressure in the intake passageway on the engine side of said governor valve and moves said governor valve toward closed position.

9. In combination a carburetor for an internal

combustion engine, said carburetor having an intake passage way, a source of fuel, a power jet for said carburetor and communicating with said source of fuel and the carburetor intake passage-way, a governor housing including an intake passageway positioned between the carburetor and the engine, a governor throttle valve in the passageway in said housing, suction responsive means connected to said governor valve, a conduit connecting said suction responsive means with the intake passageway on the engine side of the governor valve, suction responsive valve means controlling the flow of fuel through said power jet, and a second conduit connecting said first conduit with said suction responsive valve means whereby as the governor throttle valve moves toward closed position to increase the vacuum in the said passageway on the engine side of the governor throttle valve the power jet closes to lean out the mixture.

10. A governor for an internal combustion engine having an intake passageway comprising, a governor throttle valve in said passageway of the butterfly type arranged to swing about a fixed axis in said intake passageway, an orifice in said housing passageway on the engine side of said governor throttle valve and positioned so that the portion of the governor throttle valve on the engine side of the valve axis swings away from said orifice as the governor valve moves toward closed position, a suction device for controlling said governor valve, a conduit connecting said orifice and the suction device whereby the suction device is actuated by changes in pressure obtaining in the intake passageway on the engine side of the governor throttle valve and a connection between the suction device and the governor valve whereby as the pressure falls in the intake passageway on the engine side of the governor throttle valve the suction device tends to move said governor valve toward closed position.

11. A governor for an internal combustion engine comprising a housing having an intake passageway, a governor throttle valve in said passageway of the butterfly type arranged to swing about a fixed axis in said intake passageway, an orifice in said housing on the engine side of said governor throttle valve and positioned so that the portion of the governor throttle valve on the engine side of the valve axis swings away from said orifice as the governor valve moves toward closed position, a second orifice in the governor housing on the atmosphere side of said governor valve and positioned with respect to said governor valve so that as the valve moves toward closed position the portion of the governor valve on the atmosphere side of the governor valve axis swings away from said second orifice, a suction device for controlling said governor valve, a conduit connecting said orifices with said suction device, a connection between the suction device and the governor throttle valve whereby the orifice between the governor valve and atmosphere plays the role of an air bleed to the other orifice when the said governor valve moves toward closed position and said orifice between the governor valve and atmosphere ceases to be an air bleed and becomes a suction orifice when the governor valve moves toward open position and whereby neither of said orifices is effected by the Venturi action between said governor throttle valve and the walls of the intake passageway as the governor valve moves toward closed position.

12. The combination as set forth in claim 2 including a check valve in said conduit between

the second mentioned orifice and the suction device and arranged to open when the suction device is subjected to high vacuum and a by-pass conduit about said check valve and connected into said first-mentioned conduit on opposite sides of said check valve.

13. A governor for an internal combustion engine having an intake passageway, comprising a governor throttle valve in said passageway of the butterfly type arranged to swing about a fixed axis in said intake passageway, said governor throttle valve being unbalanced so that the velocity of the fluid flowing through the intake passageway and the intake passageway suction tends to close said valve, an orifice in said passageway on the engine side of said governor throttle valve and positioned so that the portion of the governor throttle valve on the engine side of the valve axis swings away from said orifice as the governor valve moves toward closed position, a second orifice in said intake passageway on the atmosphere side of said governor valve

5 and positioned with respect to said governor valve so that as the valve moves toward closed position the portion of the governor valve on the atmosphere side of the governor valve axis swings away from said second orifice, a suction device for controlling said governor valve, a conduit connecting said orifices with said suction device, a connection between the suction device and the governor throttle valve whereby as the pressure falls 10 in the intake passageway on the engine side of the governor throttle valve the suction device tends to move said governor valve toward closed position and the orifice between the governor valve and atmosphere plays the role of an air bleed to the other orifice when the said governor valve moves toward closed position and said orifice between the governor valve and atmosphere ceases to be an air bleed and becomes a suction orifice 15 when the governor valve moves toward open position.
